Primary Examiner — Ryan Harvey(74) *Attorney, Agent, or Firm* — Timothy T. Wang; Ni, Wang & Massand, PLLC(57) **CLAIM**

The ornamental design for an elliptical machine shell as shown and described.

DESCRIPTION

FIG. 1 is a rear and upper perspective view of the elliptical machine shell showing my new design;

FIG. 2 is a front and lower perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken line showing of portions of the elliptical machine shell forms no part of the claim.
